UNITED STATES PATENT OFFICE.

THOMAS SEYMOUR KNAP, OF BROOKLINE, MASSACHUSETTS, ASSIGNOR TO THE LAMSON COMPANY, OF SYRACUSE, NEW YORK, A CORPORATION OF MASSACHUSETTS.

CONVEYER SYSTEM.

Application filed July 28, 1921. Serial No. 487,810.

This invention relates to conveyer systems and is especially concerned with systems in which mechanism is employed for automatically switching or diverting the articles conveyed from one part of the system to another. It is the chief object of the invention to devise a system in which the switching or diverting of conveyers in a predetermined manner can be performed without interruption or attention, and especially to provide means for preventing the bunching or jamming of the carriers at the switching points. The invention involves both a novel organization of conveyer system and also a novel mechanism for spacing the carriers in the system.

The nature of the invention will be readily understood from the following description when read in connection with the accompanying drawings, and the novel features will be particularly pointed out in the appended claims.

Referring now to the drawings,

Figure 1 is a plan view of a portion of a conveyer system including features embodying the present invention;

Fig. 2 is a side elevation of the switching mechanism shown in Fig. 1;

Fig. 3 is a plan view of a carrier spacing mechanism forming part of the conveyer system; and

Fig. 4 is a side elevation of the mechanism shown in Fig. 3.

The system shown comprises a conveyer belt 2 having upper and lower reaches, as best shown in Fig. 4, the upper reach being supported on a series of rolls 3, and the lower reach on similar rolls 4. The upper reach of the belt travels in the direction indicated by the arrow 5, Fig. 4, and in the arrangement shown the carriers A are delivered to this belt by a roller conveyer 6.

The belt 2 delivers carriers to one or more stations, one of such stations being designated at 7, Fig. 1, and consisting of a conveyer of the roller type which diverges from the main conveyer 2. For the purpose of diverting carriers into the station, a switch mechanism is provided comprising a switch bar 8 secured fast to an upright rod 9 which preferably is mounted at its upper and lower ends in ball bearings that are supported in a suitable frame work. This construction enables the diverter arm or switch bar 8 to swing freely from the full line position, Fig.

1, to the dotted line position and back again. A truss rod 10, Fig. 2, connects the diverter arm with the upper part of the rod 9 and steadies the arm or bar. Another arm or actuator bar 12, hereinafter designated the operating arm, is pivoted at 13, Fig. 2, in the forked upper end of a post 14 which is mounted in bearing brackets 15—15 secured to a stationary support 16 so that the post can rotate about its vertical axis. The arm 12 thus is enabled to swing both in a horizontal plane about the pivot 14 and also in a vertical plane about the pivot 13. This arm is extended beyond the pivot 13 and has a weight 17, Fig. 1, adjustably secured thereto and of such a mass as to nearly counter-balance the weight of the arm 12 so that the tipping movement about the pivot 13 will require very little effort. A truss rod 18 is also connected with the rod 12 to steady it.

The operating arm 12 is connected with the switch arm 8 through a strap 19, Fig. 1, and a post 20, the post being secured rigidly to the arm 8 and projecting into the slot formed between the parts 12 and 19, as clearly shown in Fig. 1. Normally the operating arm 12 is held in the position in which it is shown in full lines, Fig. 1, by means of a weight 21, Fig. 2, connected to this arm through a cord or chain 22 running over a pulley 23 supported on the upper end of the frame piece 24.

The carriers A each consists of a box having dissimilar ends, one end being square while the upper part of the box at the opposite end is bevelled, as indicated at 25, Fig. 2. The full boxes are placed on the conveyer belt 2 in the direction indicated by the arrow 26, while the empty boxes are placed in the direction indicated by the arrow 27. In other words, the full boxes travel on the conveyer belt with their square ends foremost, while the empty boxes travel with their bevelled ends foremost. Consequently, when a full box reaches the operating arm 12 it will swing this arm across the conveyer belt 2, as indicated by the direction of the arrow 28, Fig. 1, carrying the switch arm 8 with it, and thereby moving this arm into such a position that it will divert the carrier A into the station 7. The movement of the switch arm produced in this manner is limited by a stop 29. As soon as this operation has been completed, the counter-weight 21 swings both the arms 8 110

and 12 back again to their original or normal positions.

When an empty box is carried to the switch mechanism by the conveyer belt 2, 5 the inclined face 25 which, as above stated, is foremost, will strike the arm 12 and tip this arm upwardly into the position indicated in dotted lines in Fig. 2, and the box then will pass under this arm and continue 10 its travel along the conveyer belt 2. The empty boxes, therefore, will not be diverted. Since the diverter arm 8 is positioned only a relatively short distance above the surface 15 of the belt 2, its action on the carriers is very positive.

It is desirable at certain times to render this diverting mechanism inoperative, as for instance, when the station 7 is filled with carriers, and also immediately after a box 20 has entered this station and during which time it is desired that other full boxes be allowed to travel along the belt to supply other stations. For this purpose a horizontal rock shaft 31 is mounted in a part of the 25 frame work and has rigidly secured thereto a plate or arm 32 in position to be struck and lifted by the edge of a box or carrier immediately after it has entered the station. The movement thus imparted to the rock 30 shaft 31 is transmitted through an arm 33, Fig. 2, fast on this rock shaft, a link 34, a bell crank 35, a rod 36, and a bell crank 37 to an upright rod 38, the upper end of which is turned over as indicated at 39, Fig. 1, and 35 passes through a staple 40 secured to the rearward end of the arm 12. The direction of this movement is such as to tip the operating arm 12 into its raised or inoperative position, as indicated in dotted lines in Fig. 40 2, and it will be held in this position until the carrier has moved out of engagement with the plate 32. During this period, therefore, succeeding carriers will travel uninterrupted along the conveyer belt 2 whether 45 they are full or empty.

It is desirable for several reasons that the carriers be separated from each other on the conveyer belt by at least certain minimum space intervals. For instance, if a full 50 box follows immediately behind an empty one, the operating arm 12 may not drop in time to catch it. For this purpose an automatic spacing mechanism of novel construction is provided which is best shown in Figs. 55 3 and 4. This mechanism comprises a gate 42 which is substantially U-shaped and straddles the conveyer belt, its two vertical legs, one of which is shown at 43, Fig. 4, resting, respectively, on the surfaces of two 60 cams 44 positioned at opposite sides of the conveyer. Both of these cams are fixed to a shaft 45 which is supported in suitable bearings. The gate is guided in the frame 65 for up and down movement. A gear 47 secured fast to the shaft 45 is driven by a

pinion 48 secured to another shaft which carries a roll 49 that runs in contact with the lower reach of the belt and is driven thereby. This mechanism thus imparts a relatively slow rotative movement to the 70 cams 44.

It will be observed from the shape of the cams that the gate 42 is normally in its lowermost position, and that in this position it will catch each carrier A and stop it 75 for a length of time depending upon the angular position of the cams 44 at the moment that the carrier strikes the gate. When the cam raises the gate 42, the belt moves the carrier along under the gate and 80 the gate descends again in time to catch the next adjacent carrier and retain it for a certain length of time. This mechanism thus operates automatically to space the carriers along the conveyer belt and prevent any 85 bunching of them at the switching mechanism, it being understood, of course, that this spacing mechanism is placed in front of the first switch so that it acts on the carriers before they reach the switch. By using a 90 gate 42 of the proper height, the mechanism will operate to space only full boxes and will allow the empty boxes to travel along the conveyer, the bevel 25 raising the gate 42 in the same way that it raises the 95 operating arm 12 of the switch mechanism. Usually, however, it is preferable to space both the full and empty boxes.

It will now be appreciated that this invention provides a conveyer system which 100 will operate with great certainty and reliability, which is of very simple construction, and which is entirely automatic in operation. The construction is such that wear and depreciation are very slow indeed, and 105 attention is required at only very infrequent intervals.

It will also be understood that while I have herein shown and described the best embodiment of the invention of which I am 110 at present aware, that this embodiment may be modified in many particulars without departing from the spirit or scope of this invention.

What is claimed as new is:

1. A conveyer system comprising means for moving articles in a predetermined path, a gate member extending across the path and reciprocable from a normally elevated position into the path of the carriers and back to said elevated position, and means for reciprocating said gate. 115
2. A conveyer system comprising means for moving articles in a predetermined path, a gate member, reciprocable from a normally elevated position into the path of said articles selectively to engage the articles thereon and back to said elevated position, and means for reciprocating said gate member toward and from said path in a plane 120
3. A conveyer system comprising means for moving articles in a predetermined path, a gate member, reciprocable from a normally elevated position into the path of said articles selectively to engage the articles thereon and back to said elevated position, and means for reciprocating said gate member toward and from said path in a plane 125
4. A conveyer system comprising means for moving articles in a predetermined path, a gate member, reciprocable from a normally elevated position into the path of said articles selectively to engage the articles thereon and back to said elevated position, and means for reciprocating said gate member toward and from said path in a plane 130

substantially perpendicular to the plane of said path.

3. A conveyer system comprising means for moving material in a predetermined path, a gate having a stop element extending transversely of said path and substantially parallel thereto, and perpendicular guide members projecting from the opposite ends respectively of the stop members, fixed guides for said guide members, and means for simultaneously reciprocating said guide members in their guides.

4. A conveyer system comprising means for moving material in a predetermined path, a U-shaped gate having a cross bar and parallel legs, guides within which the respective legs slide, and means engaging the legs to reciprocate the cross bar toward and from the plane of said path.

5. A conveyer system comprising a belt conveyer, a gate of inverted U-shape having a cross bar extending transversely across and above the belt, and parallel legs disposed at either side respectively of the belt, guides in which the respective legs slide, and cam means for reciprocating the gate to move its cross bar toward and from the upper surface of the belt.

6. A conveyer system comprising a belt conveyer, a gate having a stop element reciprocable toward and from the upper surface of the belt, a shaft extending transversely across and below the belt, cam means carried by the shaft for reciprocating the gate, and means for turning the shaft.

7. A conveyer system comprising a belt conveyer, guides at opposite sides thereof, a gate having slide members engaging the respective guides, the gate being reciprocable toward and from the plane of the conveyer, cams engaging the respective slide members for raising the gate, and means receiving its motion from the conveyer for simultaneously actuating said cams.

8. A conveyer system comprising a belt conveyer, a gate of inverted U-shape having a cross bar extending across the belt and parallel legs disposed at opposite sides respectively of the belt and perpendicular thereto, guides for said legs, cams engaging the lower ends of the respective legs, a shaft upon which the cams are mounted, a gear carried by the shaft, a pinion meshing with the gear, and a pulley fixed relatively to the

pinion and engaging the surface of the belt whereby to transmit movement from the belt to the pinion.

9. A conveyer system, comprising means for moving material in a predetermined path, a gate member adapted to extend substantially across the width of the path and reciprocable from a normally elevated position perpendicularly into the path and from the path, means for reciprocating said gate and means governing said reciprocation according to the movement of the material along said predetermined path.

10. A conveyer system, comprising means for moving material in a predetermined path, a gate member reciprocable perpendicularly across and from the path, means permitting said gate member to be moved from said path by engagement with the moving material thereon, and independent means for positively reciprocating said gate.

11. A conveyer system, comprising means for moving material in a predetermined path, a gate member reciprocable perpendicularly across and from the path, means permitting said gate member to be moved from said path by engagement with the moving material thereon, and independent means for positively reciprocating said gate, and means governing the positive reciprocation thereof, according to the movement of the material along the predetermined path.

12. A conveyer system, comprising means for moving material in a predetermined horizontal path, a gate member vertically reciprocable perpendicularly across said path, means permitting said gate member to be lifted from said path by suitable engagement with the moving material thereon, and means for positively reciprocating said member independently of said material.

13. A conveyer system, comprising means for moving material in a predetermined horizontal path, a gate member vertically reciprocable perpendicularly across said path, means permitting said gate member to be lifted from said path by suitable engagement with the moving material thereon, means for positively reciprocating said member independently of said material, and means governing said reciprocating means in step with the means for moving material along said path.

THOMAS SEYMOUR KNAP.
